UNITED STATES PATENT OFFICE.

GEORGE W. SCOTT, OF CLEVELAND, OHIO.

SIDE CURTAIN FOR MOTOR VEHICLES.

Application filed May 3, 1920. Serial No. 378,381.

To all whom it may concern:

Be it known that I, GEORGE W. SCOTT, a citizen of the United States, residing at Cleveland, in the county of Cuyahoga and State of Ohio, have invented certain new and useful Improvements in Side Curtains for Motor Vehicles, of which the following is a specification.

My invention relates to improvements in a side curtain for automobiles of the type which is attached to an upright support arranged on the door so as to open and close with the door, the invention relating more particularly to an arrangement for reinforcing the curtain at the upper end of the support.

The object of the invention is to provide a curtain reinforcement in the nature of a metallic socket to receive the upper end of the supporting rod which will be simple in its construction and effective in its operation.

Referring to the drawings:—

Fig. 1 is an inside view of a portion of an automobile body and one of its doors, with the door partly broken away, together with a curtain support and curtain, showing my improved reinforcement for the curtain.

Fig. 2 is a side view in detail of a portion of the curtain and its support together with reinforcement for the curtain, the view being one looking at the outside of the curtain.

Fig. 3 is a section on the line 3—3 of Fig. 2.

Fig. 4 is a view similar to Fig. 2 but looking at the inside of the curtain.

Fig. 5 is a detail of the metallic blank forming my improved reinforcement before it is bent upon itself and secured to the curtain.

The type of curtain and support to which my invention has been applied is illustrated in Fig. 1, in which 1 represents a portion of the vehicle body, 2 the frame of the door, 3 the outer metallic panel of the door, 4 the inner covering of leather, 5 the metallic strip which covers the top edge of the door, 6 a clamping device secured to the inner edge of the door and constructed in the manner illustrated in my pending application Ser. No. 360,082, filed Feb. 20, 1920, and 7 a metallic supporting rod the main portion of which projects in a vertical direction, with the lower end bent and secured to the clamp 6 in the manner described in the application referred to. The curtain is indicated by 8, and is secured in the usual way along

its rear edge by buttons and has its forward edge provided with a strip of curtain material 9 having its edges stitched to the curtain so as to provide a vertically-arranged pocket for the reception of the vertical supporting rod 7; the upper edge of the strip 9 being also sewed to the main curtain portion.

In the commercial use of supports of this character it has been found that the upper end of the rod 7 has a tendency to break through the upper end of the curtain pocket, allowing the curtain to sag down at its forward edge, and to overcome this difficulty, and also provide for stiffening the forward edge of the curtain, I provide a reinforcement for the curtain about the upper portion of the pocket of a nature now to be described.

Referring to Fig. 5, 10 represents in a general way a metallic socket portion which has been stamped or punched from a metal sheet so as to form a reduced central portion 11 and two end portions each consisting of a central socket member 12 and 13 of curvilinear shape, preferably of concavo-convex form, and side wings 14 and 15. Formed in each of the wings 14 and their channel portion 12 are V-shaped cuts to provide a pair of pointed tongues 16, and formed in each of the wings 15 is a slot 17.

In applying the socket, the blank as shown in Fig. 5 is partly bent upon itself upon a line forming the transverse center of the intermediate portion 11 and slipped over the upper edge of the curtain so that the socket portions 12 and 13 will coincide with the curtain pocket with the wings 14 and 15 lying along the opposite sides of the pocket; the tongues 16 having first been bent so as to stand at right-angles to the respective wings 14. Two halves are then firmly pressed together so that the tongues 16 will puncture the material of the curtain and its strip 9 and project through the slots 17, after which the pointed ends of the tongues are bent against the wings 15, as indicated in Fig. 4.

By the construction described it will be seen that the intermediate portion 11 will form a reinforcement for the upper end of the curtain pocket so as to prevent the supporting rod 7 from puncturing the end of the pocket, and that the wings 15 serve to stiffen the edge of the curtain and maintain it in its proper overlapping position with the curtain or other part immediately in

front of it. To prevent unduly weakening the wings it will be observed that the tongues are largely formed from the intermediate portion 12 and the comparatively narrow slots 17 are extended lengthwise of the wings 15.

Having thus described my invention, I claim:

1. In a device of the character described, 10 a reinforcing member consisting of adjacent socket portions arranged to enclose a portion of the curtain material, and an intermediate connecting portion to form a closed end enclosing both the end of rod and curtain.
2. In a device of the character described, 20 a reinforcing metallic member for flexible articles such as a curtain, which has a supporting member, consisting of adjacent parts which form a socket to enclose a portion of the flexible article and surround that part of the supporting member associated therewith, and a reinforcing connecting portion at one end of said socket, clamping the end 25 of the supporting member and upper part of article, the other end of said socket being left open to receive said supporting member.
3. In a device of the character specified, 30 a metallic socketed reinforcing member arranged to receive a supporting rod for a flexible article comprising a curvilinear portion which surrounds the end of said rod and an end connecting portion, the end portion being arranged to extend across the end 35 of said rod, a part of the material of the flexible article being clamped between said socketed member and the end of said rod.
4. In a device of the character described, 40 the combination, with a supporting rod, a flexible article formed with a pocket, a metallic reinforcing member having portions to form a socket and also having formed integrally therewith a reinforcing connecting portion arranged to lie across the end of 45 said rod, and clamp said pocket portion to

the end of said rod, said socketed portions also enclosing a portion of the flexible article, and means for securing said reinforcing member to the material of said flexible article.

5. In a device of the character described, the combination, with a flexible article provided with a double thickness of material to form a pocket for a support, of a sheet metal reinforcement for said article consisting of 55 a pair of socket portions having side wings and a central connecting portion, said socket portions and their wings being bent upon one another with the flexible material between the same so that the socket portions 60 will coincide with each other and with the said pocket of the flexible material, and means for clamping the wings together.

6. In a device of the character described, the combination with a curtain of flexible 65 material having a vertically arranged pocket and an upright support located in the pocket, of a reinforcing channeled member secured to said curtain and embracing the pocket and support at a point in proximity to the upper end of the support; the channeled portion being formed open at the lower end and closed at the upper end thereof to reinforce the pocket at that point.

7. In an automobile side curtain having 75 a curtain door to move with the automobile door, a door rod adapted to be mounted on the automobile door, and a metal pocket formed of a sheet of metal bent to form a channel to receive the end of the door rod 80 and having oppositely extending flanges secured to the curtain door and an end extension bent to close the end of the channel and to bear on the end of the door rod.

In testimony whereof, I have hereunto 85 set my hand this 26th day of April 1920.

GEORGE W. SCOTT.
